ORTHODONTIC MOLD APPLIANCE

Thomas Hill and Chester P. Lucas, New York,
N. Y.

Application December 11, 1935, Serial No. 53,861

9 Claims. (Cl. 18—34.1)

This invention relates to devices for the production of orthodontic models, and other record models and articles.

One object of the invention is to provide a device of the character described having improved means for producing such models or articles in various sizes according to predetermined guide or scale means or both.

Another object of the invention is the provision of a device of the nature set forth having improved scale means for rapidly obtaining different sizes directly and additively, for setting a mold for the models or articles.

Another object of the invention is to furnish a device of the type mentioned having parts adjustable in an improved manner for molding records or articles of different sizes with especial reference to orthodontic models for children as well as adults.

A further object of the invention is to provide a device of the class alluded to having relatively few and simple parts, and which is inexpensive to manufacture and assemble, easy, convenient, accurate, and rapid in use, durable, reliable and efficient to a high degree in operation.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawings, wherein like parts are designated by the same reference characters throughout the several views.

In the drawings:

Figure 1 is a view in front elevation showing a device embodying the invention.

Fig. 2 is a view in rear elevation thereof.

Fig. 3 is a top plan view of the device.

Figs. 4, 5, 6, 7 and 8 are perspective isometric views of parts of the device.

Fig. 9 is a view in elevation with parts in section and other parts in dot dash lines showing details of the device.

Figs. 10 and 11 are sectional views taken on the respective lines 10—10 and 11—11 of Fig. 9.

Fig. 12 is a plan view of a scale device embodying the invention, with some marks omitted.

Figs. 13 and 14 are sectional views taken on the respective lines 13—13, 14—14 of Fig. 12.

Fig. 15 is a fragmentary sectional view taken on the line 15—15 of Fig. 14.

Figs. 16 and 17 are views in elevation showing

successive steps in making orthodontic molds, with parts in dot dash lines.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawings, therefore, are submitted merely as showing the preferred exemplification of the invention.

Referring in detail to the drawings, 20 denotes a device embodying the invention. The same 15 may include a base 21 reenforced by a continuous marginal flange 22 along the front, back and sides thereof. Rigidly mounted on said base is a back 23 reenforced by marginal bottom and side and top flanges 24, the back having a central vertical 20 guide slot 25, see Fig. 1, and the top flange being cut away at 26 in spaced relation to the slot. The back is perpendicular to the plane of the base, and the flange reinforcements prevent relative bending or springing, and permit these parts to 25 be made of relatively light material or sheet metal.

Coacting with the base and back are a plurality of like guide or wing members 27, only the right hand member being shown in Fig. 4. Each wing member has a plurality of upright extending flanges which, in plan, are at an angle to each other, and with the flange 28 being at an angle to the back 23. Thus a double corner formation is obtained in an orthodontic model base, according to approved practice. The flanges 28 always make continuous line contact with the back 23 and the wing members are perpendicular to the base 21 and in constant engagement therewith. It is noted that the flanges 28, 29 are both relatively narrow to permit molding of bases of different size without binding by the flanges, especially the flange 29.

At its lower end each member 27 includes a flange or mold section 30 extending forwardly 45 of the back and desirably in the plane of its flange 29. These sections 30 normally converge toward each other.

For adjustably securing the members 27 to the base 21, a reinforcing angle member 31 may be 50 secured to each section 30, with the horizontal flange provided with an open ended slot 32. Permanently threadedly connected to the base 21 are clamping screws 33 which pass through a large relative movement of the members 27 toward 55

and away from the screws 33, angle plates or washers 34 may be provided, each having an open ended slot 35 to receive a clamping screw, and a lip 36 at the closed end of the slot, said 5 lip being of the same thickness as the angle member 31. Thus the members 27 and 34 may be adjusted according to any desired spacing or angularity between the members 27 and clamped 10 tight by the screws 33 having their heads formed 15 with transverse rods for powerful screw activation.

It is now seen that the mold basin is closed at the back and sides by the members 23 and 30, but is open at the front. To close the latter one 15 or another of the members 37, 38 may be used. The member 37 is of arcuate form and is used in molding the lower base, while the member 38 is of angular form and is used in molding the upper base, to thus differentiate the bases from 20 each other. Both members are of the same height, and their concavities are of the same depth, and the distances between their ends are equal. Each member 37, 38 has a like frontward horizontally projecting internally threaded central boss 39 for holding its member down upon the base 21 and with the ends or points 40 of the member in snug engagement with and between the members 30 as shown in Fig. 3. In practice, the members 27, and 37 or 38 are set in required 30 positions and thereafter secured tight in these positions.

To adjustably conveniently set a member 37 or 38, a rod 41 may have its threaded end 42 removably screwed into a boss 39 of one or the 35 other member 37, 38. This rod may be received in a notch 43 of a block 44 that may be rigidly secured to the base 21 at the forward end thereof. A latch plate 45 may be pivotally connected at 46 to the block 44 for swinging thereover with the 40 adjustable nonremovable screw or nut 47 received in the open ended slot 48 of the latch plate. Hence, upon tightening the element 47, the plate 45 bears tightly down upon the rod 41 to hold it securely in the notch 43 and against relative 45 longitudinal movement. In this manner the elements 37, 38 and 41 may be alined with the center of the base 21, and the rod 41 being perpendicular to the back 23.

In order to assure a correct horizontal relation 50 of an anatomical portion of an orthodontic record, a guide plate 49 is provided having side points 50 and a front point 51 for seating on the corresponding tooth portions of the anatomical portion to thus horizontally press the latter downward into the mold cavity, defined by members 23, 27 and 37. Hence the member 49 is a flat horizontal vertically movable plate, having a rear straight edge 52 for movement along the back 23. Said plate 49 may have an internally threaded 60 upper substantially central boss 53 for releasable connection with a guiding and actuating means therefor.

For guiding the member 49, a vertical guide bar 54 may be suitably rigidly connected to the base 65 21 in the rear of the back 23, and with the guide bar extending upward in central vertical register with the slot 25 and somewhat above said back and in spaced relation thereto. A sleeve 55 slidably along the bar 54, carries an arm 56 70 projecting forwardly through the slot 25, and rigidly carrying at its forward end a sleeve or hub 57. Extending snugly through the latter is a vertical screw 58 having a head 59 whereby the screw can be threaded into the boss 53, with the 75 lower face of the sleeve 57 registering with said

boss to aid in horizontally holding the guide plate 49. Since downward actuation of the latter may be caused by pressing on the nut 59, wings 60 may be provided on the element 56 to extend in opposite directions in sliding engagement with the rear face of the back 23, to thus aid in overcoming any possible cantilever stress on the member 56 and bar 54. The plate 49 and its supporting means are removable as a unit with the sleeve 55 moving upward off from the bar 54, and the member 56 traveling upward out of the slot 25. Upon so removing the guide plate 49, the mold cavity 10 is fully conveniently exposed for work.

Having measured the height of the orthodontic model which is to be produced, it is preferred to 15 provide means to limit the downward travel of the guide plate 49 accordingly. We may use a simple clamp 61 having a clamping screw 62, but in order to prevent the screw from biting into the bar 54, and interfering with smooth sliding of the 20 sleeve 55, we prefer to use a second bar 63 to mount and receive the clamping action of the clamp 61. Said clamp may have a projecting portion slidingly engageable with the guide bar 54 in the path of the sleeve 55 to thus limit downward movement of the latter according to the 25 clamp setting.

To facilitate setting of the lowermost point of travel of the guide plate 49, we may correlate therewith a pair of marks or perforations 64, 65, 30 see Fig. 2, one being in a wing 60 and the other in the back 23. The relationships may be such that upon elevating and tightening the clamp 61 to support the otherwise free plate 49 at a point such that the distance between the perforations 35 64, 65 is equal to a given measurement, an orthodontic model of required height will be obtained.

We will now describe the gage for readily obtaining the required measurements for setting the lowermost point of travel of the plate 49. 40 Said gage 66 may include a plate 67 having corner supporting feet 67a. Along this plate there may extend a row of marks or perforations 68 parallel to the adjacent edge 69 of the plate, and a plurality of rows of perforations 71, 72 at different angles with the row 68. The arrangement of the perforations is such that corresponding perforations in the rows 68, 71, 72 will all lie along parallel lines, perpendicular to the straight edge 69.

Associated with the plate 67 is a slide element 73 providing a straight edge transverse to said rows 68, 71, 72 and transversely movable along said rows. Said element may have end portions 74, 75 undercut at 76 to receive and slidably engage opposite parallel straight edge portions 69, 77 of the plate 67.

To clamp the element 73 to plate 67 in a set position, a sleeve 78 may be mounted on the portion 74, said sleeve having opposite open ended slots 79, see Fig. 15, to receive an adjacent edge portion 77 of the gage plate. A screw 80 may be fixedly threaded into an end of the portion 74, and a runner nut 81 may be turned to bear downward on the sleeve 78 to cause the same to frictionally clamp with the gage plate at the closed ends of the slots 79.

Along the portion 75 is slidable a sleeve 82 that may be clamped in fixed position to the element 73 by a set screw 83. The sleeve 82 may 70 have a laterally extending wing 84 having a mark or perforation 85 for a purpose later described. The element 73 may be capped at its end at 86 to prevent removal of the sleeve 82. To prevent angular motion, the element 73 and parts 74, 75

75, 78, 82 may be of square or rectangular cross section.

A typical manner of using the invention will now be described. The lower anatomical portion 5 87 is measured as with a pair of dividers to obtain the distance A. Opposite points of the dividers are then moved along the rows 68, 71 of the gage plate 67, until the divider points register with corresponding perforations. The nut 81 is now 10 loosened and the straight edge element moved to the immediate left of the perforations so registering with the divider. Then the nut 81 is screwed tight so that element 73 is now clamped in position for all measurements for the orthodontic models. The divider is now opened further to register with the perforation of row 68 and the corresponding perforation of row 72, along the element 73, the divider being thus set to the distance B. This setting B gives the height 15 20 of the lower orthodontic model of Fig. 16, including the thickness of the base 88 shown in dot dash lines. The clamp 61 is now set to cause the distance between the perforations 64, 65 to be equal to B. If now the molding material is placed 25 in the mold cavity, and the portion 87 superimposed, and the guide plate 49 moved downward as far as it will go, a lower orthodontic model L will be obtained whose height will be the measurement B.

30 It is now desired to make the upper orthodontic model U. For this purpose, the model L is placed over the upper anatomical specimen 89 with the parts 87, 89 in occlusion. The divider is now used to obtain the measurement C which includes 35 model L and specimen 89. The operator now loosens the screw 83 and sets and clamps the member 82 at a position such that one pointer of the set divider is in perforation 85 and the other in the above mentioned perforation of the 40 row 71, defining the distance C. Now the operator opens the divider to obtain a measurement D, being the distance from 85 to the corresponding perforation of row 72. Due to the slide 45 73, it will be seen that no confusion as to the perforations desired is possible. Now the clamp 61 is reset to obtain distance D between the perforations 64, 65. Molding material is placed in the mold, and the model L and specimen 89 are placed as a unit as in Fig. 17 into the mold and 50 the guide plate 49 moved downward as far as it will go, thus resulting in the molding of a base 90 to complete the upper model U.

It will be noted that with specimens 87, 89 in proper occlusion, the upper and lower model 55 surfaces 91, 92 are perfectly parallel, and the rear faces 93 lie in a plane, perpendicular thereto. Likewise the corners 93a are in true vertical alignment. Hence a rapid check up can be made 60 whether the specimens 87, 89 are in the actual or proper occlusion or relation to each other, upon inspecting the models at any future date to observe orthodontic progress.

As regards the actual molding operation it is thought that the same will be amply clear from 65 the descriptions hereinbefore given.

We claim:

1. Orthodontic molding apparatus including a horizontal base, a back projecting upwardly therefrom, means for determining the contour of an article to be molded, said means including 70 separate side elements engageable with the base and the back and projecting forward from the back, a front element mounted on the base and movable toward and away from the back between the side elements, the latter being adapted to be 75

adjusted angularly to each other and having bearing engagement with the ends of the front element to provide a mold cavity, a horizontal plane movable along the back, and means for limiting the movement of the plane to produce 5 an article of a predetermined height.

2. Orthodontic molding apparatus including a base, a back projecting upwardly therefrom, and means for determining the contour of an article to be molded, including separate side elements 10 engaged with the base and back, and a separate front element engaged with the base and having end edges engaged with the side elements therebetween, means adjustably securing the front element in predetermined spaced relation to the 15 back, and means for securing the side elements for angular and linear motion so that the side elements can converge frontward toward each other at a desired angle, and according to a desired spaced relation between the side elements 20 depending upon the position of the front element.

3. Orthodontic molding apparatus including a base, a back projecting upwardly therefrom, and means for determining the contour of an article to be molded, including separate side elements, the latter having angle members having open ended slots, screws connected to the base and receivable in the slots for clamping the angle members to the base to secure the side 30 elements in desired spaced and angular relationships with each other, with the side members engaged with the base and back, a separate front element having its ends engageable with the side members to provide a mold cavity, a rod 35 secured to the front element, and a clamp on the base for slidably engaging and securing the rod to maintain the front element in desired spaced relation to the back, said clamp being so fixed as to maintain the rod at right angles to 40 the back in different positions of adjustment of the front element.

4. Orthodontic molding apparatus including a base, a back extending upward therefrom, and means for determining the contour of an article to be molded, including separate side members movable for angular and spaced adjustment relative to each other, and a front member adjustable along a fixed axis toward and away from the back, said members producing in assembled 45 50 relation a configuration corresponding to that of an orthodontic mold.

5. Orthodontic molding apparatus including a base, a back extending upward therefrom, and means mounted on the base for determining the contour of an article to be molded, including 55 separate side members movable for angular and spaced adjustment relative to each other, and a front member adjustable along a fixed axis toward and away from the back, and means for securing the front member in adjusted position, including a rod, a block secured to the base and having a passage along which the rod is 60 65 slideable, and a clamping screw for preventing longitudinal movement of the rod.

6. Orthodontic molding apparatus including a base, a back extending upward therefrom, and means mounted on the base for determining the contour of an article to be molded, including side members movable for angular and spaced 70 adjustment relative to each other, and a front member adjustable along a fixed axis toward and away from the back, and means for securing the front member in adjusted position, including a rod, a block secured to the base and 75

having a passage along which the rod is slidale and a clamping screw for preventing longitudinal movement of the rod, the side members having laterally extending base portions, and means for adjustably individually securing said base portions to said base.

7. Orthodontic molding apparatus including a base, a back projecting upward therefrom, and means for determining the contour of an article to be molded, including separate side members movable for angular and spaced adjustment relative to each other, a front adjustable securing means on the base, and one of a series of front members of different contour interchangeably connected to the securing means and adjustable thereby toward and away from the back, said front members being disposed to lie between the side members transversely thereof and in direct contact therewith.

20 8. Orthodontic molding apparatus including a base, a back extending upward therefrom, means for determining the contour of an article to be molded, means movable along the back, and means for limiting the path of movement of the 25 movable means to determine the height of the molded article, including a bar, a clamp adjustably movable along the bar, said bar and clamp

being located at the rear of the back, guide means connected to the movable means and passing through a slot in said back into proximity to the clamp for abutment therewith to limit the travel of the movable means as aforesaid, said clamp and bar being otherwise independent of the guide means.

9. Orthodontic molding apparatus including a base, a back extending upward therefrom, means associated with said base and back for determining the contour of an article to be molded, horizontal means movable along the back for exerting pressure on material in the mold, said back having a slot, an arm connected to the horizontal means and extending through said slot, a plurality of upright parallel bars secured to the base, a sleeve connected to said arm and movable along one bar, a clamp adjustable along the other bar and lying in the path of the sleeve to limit the movement of the horizontal means to determine the height of the molded article, said horizontal means being otherwise so independent of the back that pressure exerted on said means is not communicated to the back to strain the same.
